UNITED STATES PATENT OFFICE.

CLAUDE SCHEELK, OF CHICAGO, ILLINOIS.

COMPRESSION-FAUCET WASHER.

Application filed March 8, 1921. Serial No. 450,601.

To all whom it may concern:

Be it known that I, CLAUDE SCHEELK, a citizen of the United States, residing at Chicago, in the county of Cook and State 5 of Illinois, have invented new and useful Improvements in Compression-Faucet Washers, of which the following is a specification.

This invention relates to water faucets, 10 and more particularly to the means for closing the valve seats thereof.

The principal object of the invention is to provide a novel and improved faucet that will not collect dirt, sand or rust, thereby 15 insuring the cleanliness of the interior of the latter.

A further object is to provide a plug construction that will compensate for any looseness in its fastening means.

With the above and other objects in view, 20 my invention will be more fully described and illustrated in the accompanying drawings which show various embodiments thereof, and then specifically pointed out in the 25 claims, which are attached to and form a part of this application.

In said drawings:

Figure 1 is an elevation of a faucet, partly 30 in section, showing the same equipped with the valve plug which is the subject matter 35 of the present application for patent, Figs. 2 to 12 are sectional views of different forms of plugs, Fig. 13 is an inverted plan view of a valve stem, and Fig. 14 is a plan view of 40 a plug.

Referring specifically to the drawing, and more particularly to Fig. 1, the body of the faucet is shown at 17, the same containing a partition 18 provided with an opening 45 19 forming a valve seat and providing a passage for establishing communication between the inlet and outlet ends of the casing. The valve controlling the opening 19 is a plug 20 carried by a stem 21 which is 50 adapted to be raised or lowered by rotating the same in the usual manner, to withdraw the plug from the valve seat or to insert the same thereinto. The said stem 21 is provided with a circumscribing integral 55 flange 22 which has parallelly spaced grooves 23 for the reception of ribs 24 on the top of the said plug 20. The valve plug 20 has a downward taper so that it may be 60 tightly wedged in the opening 19 when it is forced downwardly, this taper being ob-

tained by giving the side of the plug 20 a substantially convex curvature. The plug 20 is secured to the lower end of the stem 21 by an axial screw 25 passing centrally through the plug and threaded into the said 60 stem. The head of the screw 25 is at the bottom of the said plug, and it is countersunk. The purpose of the rib-and-groove relation between the plug 20 and the flange 22, is to keep the said plug from turning 65 as the screw 25 is applied, or when said screw loosens somewhat from use, or when said plug shrinks from repeated operation of the valve so that said screw ceases to function as positive tightening means. 70

Fig. 2 shows a valve plug 26 similar to the plug 20 shown in Fig. 1, but secured by a screw 27 which is not countersunk.

The valve plug 28 shown in Fig. 3 is somewhat longer than the one shown in Fig. 1, the sides of the same being slightly different in shape, and is secured by a countersunk screw 29. 75

The valve plug 30 shown in Fig. 4 is similar to the plug 28 in Fig. 3, but is secured by a screw 31 which is not countersunk. 80

In Fig. 5 is shown a valve plug 32 of inverted frusto-conical shape, secured by a 85 countersunk screw 33.

The valve plug 34 shown in Fig. 6 is similar to the plug 32 in Fig. 5, but is secured by a screw 35 not countersunk.

Fig. 7 shows an inverted frusto-conical plug 36 secured by a countersunk screw 37, 90 and which is made somewhat longer than the plugs 32 and 34, and is well adapted for seats of different diameters.

The valve plug 38 shown in Fig. 8 is similar to the plug 36 in Fig. 7, but is secured by a screw 39 which is not countersunk. 95

Fig. 9 shows a valve plug 40 having its sides of concave curvature and secured by a countersunk screw 41, while Fig. 10 shows 100 a similar plug 42 secured by a screw 43 which is not countersunk.

Fig. 11 shows a valve plug 44 similar to the plug 42, but made somewhat longer to adapt it for different sized valve seats. This 105 valve is secured by countersunk screw 45.

The plug 46 shown in Fig. 12 does not differ from the plug 44, except that its securing screw 47 is not countersunk.

It is to be understood the rib-and-groove 110

expedient, 24, 23, described in connection with Fig. 1 is present in each of the modifications depicted in Figs. 2 to 12 inclusive.

Having thus described my invention I claim as new and desire to secure by Letters Patent:

1. In combination, a valve stem having its base grooved, and a valve plug carried by said stem and having its upper face 10 ribbed for insertion in the grooved base of the valve stem to prevent the said valve plug from turning.
2. In combination, a valve stem having a circumscribing flange at its base, said flange 15 having parallelly spaced grooves, and a valve plug secured to said stem having ribs on its upper face for insertion in the said

grooves of the said flange to prevent the said valve plug from turning.

3. A water faucet having a partition provided with an opening and a valve seat with a vertical rim about said opening, a valve stem having a circumscribing flange at its base, said flange having parallelly spaced grooves on the underside thereof, and a 20 tapered valve plug secured to said stem, adjustable in relation to the said valve seat and having ribs on its upper face for insertion in the said grooves of the said flange 25 to prevent the said valve plug from turning.

In testimony whereof I affix my signature.

CLAUDE SCHEELK.
